UNITED STATES PATENT OFFICE.

FRED F. BENSON, OF CHINOOK, MONTANA.

CRATE.

1,292,419.

Specification of Letters Patent. Patented Jan. 28, 1919.

Application filed March 5, 1918. Serial No. 220,540.

To all whom it may concern:

Be it known that I, FRED F. BENSON, a citizen of the United States, residing at Chinook, in the county of Blaine and State 5 of Montana, have invented new and useful Improvements in Crates, of which the following is a specification.

This invention relates to crates or shipping boxes and is especially designed for 10 use in the shipment of eggs and butter.

More specifically stated the invention provides a box or crate which is formed of a stiffened material such as tin or sheet metal and covered with cloth or other suitable fabric to provide a cushioning effect to 15 absorb shock or jar and superimposed layers or tiers of egg compartments arranged within the crate and a lid or closure removably positioned within the latter and capable of being adjustably secured in position.

A novel feature of the invention resides in the formation of separate egg compartments which consist of longitudinal partitions 20 of stiffened material, such as tin or sheet iron and which extend the entire length between opposite walls of the crate to form a firm support for the upper tiers of egg compartments, the longitudinal partitions 25 being covered with a suitable fabric and being connected by short cloth partitions to form separate compartments, the latter partition being centrally creased so that the longitudinal partitions may be 30 compactly arranged one against the other when not in use.

In the drawings:

Figure 1 is a longitudinal sectional view through a crate constructed in accordance 40 with the present invention;

Fig. 2 is a transverse sectional view of the same; and

Fig. 3 is a fragmentary horizontal sectional view illustrating one of the tiers or 45 partitions empty and partly collapsed.

Referring to the drawings in detail the crate comprises a box or receptacle 10 preferably formed of tin, sheet iron or similar material. The bottom, side and end walls 50 of the receptacle may be integrally formed, or they may be separately formed and secured together by any desired means. It is preferred to surround the upper open edge of the box or receptacle with a bead 11 55 and to cover the box both inside and out-

side with a covering of cloth or other suitable fabric as shown at 12. In order to protect the outer cover of fabric and to further stiffen the box or crate, there is provided an outer casing 13 which may be 60 formed of the same material as the crate 10.

One of the points of novelty of the invention resides in the formation of partitions which form separate compartments for the reception of eggs, these compartments being 65 formed by longitudinal partitions 14, which include tin or sheet metal strips 15 and a cloth covering 16. The strips 15 are connected by short transverse partitions 17, which are centrally creased as shown at 18 and are 70 formed of cloth or other suitable fabric and adapted to fold between the partitions 14 to permit of the latter being compactly folded against one of the walls of the box or receptacle 10.

The partitions just described are designed to be arranged within the box or receptacle in tiers and each tier is separately by a horizontal partition formed of a sheet of metal 19 and covered with cloth 20. The 80 cover or closure is adapted to be removably secured within the box or crate and like the horizontal partitions just described is formed of a sheet of metal 21, which is cloth covered as shown at 22. The closure 85 carries bolts 23, which are adapted to engage vertically aligned openings 24 provided in the walls of the box or crate, so that the said closure may accommodate partitions of different heights.

By forming the partitions 14 of a single length of stiffened material, a firm support is provided for the contents of the crate thereabove, so that in addition to being used for the shipment of eggs, the upper 95 partitions may be removed and butter or other commodities substituted, the weight being supported by the longitudinal partitions 14 so that danger to the eggs is avoided. In the use of the invention as just 100 described the utility of the adjustable feature of the closure will be apparent, as it is necessary that the said closure be tightly adjusted to prevent any movement of the parts within the crate.

Having described the invention, what is claimed is:

A crate embodying a box or receptacle including a bottom, side and end walls, each of which are covered upon their inner 110

and outer surfaces with a cloth cushioning element, individual compartments arranged in tiers within said crate, said compartments being formed of longitudinally disposed strips of stiffened material, a cloth cushioning element covering said strips, intervening transversely vertical webs of cloth

connecting the strips, horizontally arranged stiffened partitions between the tiers of compartments, a cloth cushioning element 10 covering the partitions and a stiffened adjustable cloth covered closure for the crate.

In testimony whereof I affix my signature.

FRED F. BENSON.
